(57) **CLAIM**

The ornamental design for a laser engraver machine, as shown and described.

DESCRIPTION

FIG. 1 is a perspective view of a first component of a laser engraver machine showing my new design;
FIG. 2 is another perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof;
FIG. 9 is an enlarged view of portion 9 shown in FIG. 1;
FIG. 10 is an enlarged view of portion 10 shown in FIG. 1;
FIG. 11 is a perspective view of a second component of the laser engraver machine showing my new design;
FIG. 12 is another perspective view thereof;
FIG. 13 is a front elevational view thereof;
FIG. 14 is a rear elevational view thereof;
FIG. 15 is a left side elevational view thereof;
FIG. 16 is a right side elevational view thereof;
FIG. 17 is a top plan view thereof;
FIG. 18 is a bottom plan view thereof;

FIG. 19 is a perspective view of the first component of the laser engraver machine where the first component is in a folded state;

FIG. 20 is a perspective view of the laser engraver machine where the laser engraver machine is in a first configuration of use; and,

FIG. 21 is a perspective view of the laser engraver machine where the laser engraver machine is in a second configuration of use.

The broken lines in the drawings depict portions of the laser engraver machine that form no part of the claimed design.
